UNITED STATES PATENT OFFICE.

GEORGE W. KING, OF MARION, OHIO, ASSIGNOR TO THE MARION STEAM SHOVEL COMPANY, OF MARION, OHIO, A CORPORATION OF OHIO.

BUCKET FOR DREDGES.

No. 838,120.

Specification of Letters Patent.

Patented Dec. 11, 1906.

Application filed June 2, 1906. Serial No. 319,952.

To all whom it may concern:

Be it known that I, GEORGE W. KING, a citizen of the United States, residing at Marion, in the county of Marion and State of Ohio, have invented certain new and useful Improvements in Chain-Buckets for Dredges, of which the following is a specification, reference being had therein to the accompanying drawings.

10 This invention relates to chain-buckets for dredges, and has for its object to provide a construction of the buckets of which the dredging-chain is composed whereby said buckets are strengthened and rendered more efficient and whereby their connections with each other are rendered more secure.

To these ends the invention consists in certain novel features, which I will now proceed to describe, and will then particularly point out in the claims.

In the accompanying drawings, Figure 1 is a front elevation of a bucket embodying my invention in one form. Fig. 2 is a side elevation of the same. Fig. 3 is a detail view of the journal-pin employed to connect the adjacent buckets. Fig. 4 is a detail sectional view of the same, taken on the line $x-x$ of Fig. 3 and looking in the direction of the arrows. Fig. 5 is a detail view of one of the locking-pins detached. Fig. 6 is an end view of the same, and Fig. 7 is a detail view of the locking-plug detached.

Referring to the said drawings, it will be seen that the bucket comprises a frame or base 64, a shell or body 65, and a cutter 66, the frame being of cast-steel, the body or shell of plate-steel, and the cutter of hard steel, the three parts being firmly united by riveting. The novel features of this portion of my invention consists in forming the shell or body of the bucket of a single piece pressed into shape. Heretofore these shells or bodies have been made in three sections, united together by riveting, which not only is expensive, but also renders it difficult to make a good joint, while the joints, even if originally well made, are apt to open and become leaky. By reason of my construction I obtain at small expense a smooth strong bucket and at the same time avoid leaky joints and the consequent waste of gold. A further feature of novelty in connection with the bucket relates to the means connecting the elements of the chain. Each bucket is,

as usual, provided with two apertured lugs 55 67 at its front ends to receive a journal-pin 68, to which the next member of the chain is connected. This pin is provided near each end with transverse slots 69, located on opposite sides thereof. An aperture 70 is formed 60 through each lug, so as to intersect the main aperture 71 of said lug through which the journal-pin 68 passes. Into the aperture 70 is fitted a locking-pin 72, having one of its sides flattened and tapered, as indicated at 65 73, so that when said pin is inserted in the aperture 70 its flattened side will bear against the bottom of one of the grooves 69 in the journal-pin 68, and thus clamp said pin in position. The locking-pin 72 is held in place 70 by means of a screw-plug 74, which screws into the upper end of the aperture 70, which is threaded to receive said lug.

The construction just described provides a firm and effective fastening for the journal-pin free from all projecting parts, and therefore not subject to wear. The slotting of the journal-pin on both sides permits it to be turned when one side is worn, so as to bring the unworn side into bearing relation with 80 the sleeve of the next bucket or such other part of the chain as may fit thereon.

I wish it to be understood that I do not desire to be limited to the exact details of construction shown and described, for obvious 85 modifications will occur to a person skilled in the art.

Having thus fully described my invention, what I claim as new, and desire to secure by Letters Patent, is—

1. In a dredge-bucket comprising a body portion formed of a single piece of sheet-steel, a cast-steel base, lugs at the opposite ends of said base having apertures therein, and means for connecting the apertured lugs of 95 the adjacent buckets, substantially as described.

2. In a dredge of the character described, a bucket having lugs apertured to receive a journal-pin and provided with other apertures intersecting said journal-pin apertures, in combination, with a journal-pin transversely grooved or slotted near the ends thereof, and locking-pins located in the intersecting apertures and fitting the grooves 105 of the journal-pin, substantially as described.

3. In a dredge of the character described, a bucket having lugs apertured to receive a

journal-pin and provided with other apertures intersecting said journal-pin apertures, in combination with a journal-pin transversely grooved or slotted on opposite sides near each end, locking-pins located in the intersecting apertures and flattened to fit the grooves of the journal-pin, and screw-plugs fitted in the ends of the locking-pin apertures to secure the locking-pins in position, said

locking-pin apertures being threaded to receive said plugs, substantially as described.

In testimony whereof I affix my signature in presence of two witnesses.

GEORGE W. KING.
